UNITED STATES PATENT OFFICE

172,269

BABY WALKER

Carl B. Dahlberg, Alhambra, Calif., assignor to
Hemet Aircraft Corporation, Alhambra, Calif.,
a corporation of California

Application January 4, 1954, Serial No. 38,330

Term of patent 14 years

(Cl. D14—14)

To all whom it may concern:

Be it known that I, Carl B. Dahlberg, a citizen of the United States, residing at Alhambra, county of Los Angeles, State of California, have invented a new, original, and ornamental Design for Baby Walker, of which the following is a specification, reference being had to the accompanying drawings, forming part thereof.

Fig. 1 is a top plan view of a baby walker, embodying my new design;

Fig. 2 is a view in front elevation of the same;

Fig. 3 is a view in side elevation of the same;
and

Fig. 4 is a bottom plan view of the same.

I claim:

The ornamental design for a baby walker, as shown.
